EYESHIELD

Honel A. Jackson, Detroit, Mich.

Application April 14, 1938, Serial No. 202,102

6 Claims. (Cl. 2-8)

This invention relates to an eye shield adapted for use in protecting the eyes for various types of work and for instance, welding, grinding, metal pouring, for example.

It is especially aimed to provide a structure having a mounting frame or harness relatively to which the protecting means may be swung as a whole to and from operative position, and a construction utilizing novel means for the minute adjustment of the lens-carrying frame and for the fastening of the lens in such frame.

The more specific objects will become apparent from a consideration of the description following taken in connection with accompanying drawing illustrating an operative embodiment.

In said drawing:—

Figure 1 is a plan view of the improved eye shield;

Figure 2 is a vertical sectional view taken on the plane of line 2—2 of Figure 1;

Figure 3 is a view primarily in side elevation and partly in section, taken on the plane of line 3—3 of Figure 1;

Figure 4 is an enlarged detail section taken on the plane of line 4—4 of Figure 3;

Figure 5 is a fragmentary end elevation of the lens-carrying or protector frame, and

Figure 6 is a fragmentary side elevation of a modified form of side or cheek piece.

Referring specifically to the drawing, a suitable mounting frame or harness is provided as at 10 adapted to fit or rest on the top of the head. For example, such frame may have a horizontal arcuate member 11, a vertical arcuate member 12 riveted or otherwise fastened at its ends thereto as at 13, and a short arcuate member 14, riveted or otherwise fastened as at 15 and 16, to the members 12 and 11, respectively. Said members 11, 12 and 14 may be made of any desired, preferably flexible material. A soft band of leather or the like may be provided as at 17 over the front portion of the member 11. In order to better secure said harness 10 in place, an elastic band 18 is preferably employed, being anchored at opposite ends to the section 11, one end being detachable and adjustable as at 19.

Suitably pivoted as at 20 to the section 11 are side or cheek pieces 21, preferably of transparent material, and for instance celluloid. If desired, spring washers 22 may be provided about the pivot elements 20. At any rate, the pivotal connection at 20, frictionally holds the side pieces 21 in adjusted positions, although permitting them to be swung on the pivots.

The lens-carrying protector frame or hood is

provided at 23, being made of any desired material for instance aluminum or other metal, hard rubber, Bakelite or the like. Such frame carries a lens as at 24 and it has a marginal flange 25 extending completely around it, which is cut out as at 26 and 27, to fit the forehead and is further notched as at 28, to fit and rest on the bridge of the nose.

The sides of such flange 25, specifically indicated at 29, have rivets or other fastenings 30 passing therethrough and also passing through enlarged openings 31 in the side pieces 21. The openings in the end members 29 through which rivets 30 pass are indicated at 32 and are preferably vertically elongated and such end pieces at the rear are notched as at 33. Spring members are employed at 34 which are generally of U-shape and receive the end pieces 29 therein, the bridge of such springs extending into the notches 33. Said rivets 30 pass through the arms 35 and 36 of such spring members 34 and the arms 36 at their forward ends tend to spring away from the adjacent end piece 29 and frictionally engage the side edges of the lens 24 to releasably hold it in place.

Said arms 35 extend outwardly beyond the side or cheek pieces 21 and terminate in grips 35'. Inwardly of such grips, said arms 35 have lugs 37 struck outwardly therefrom. Said lugs are adapted to engage any opening of a series of openings 38 provided in the side or cheek pieces 21. Said openings 38 may be arranged in any desired manner and in one or more rows, relative sliding movement of the side pieces and frame 23 being permissible due to the enlarged slots 31.

Said slots 32 and 38 may be of any desired shape and arrangement and as shown at 38' in Figure 6, they may be rectangular or elongated. In addition, the side members or cheeks 21 as indicated at 21a in Figure 6 may be of any desired or preferred shape.

In the use of the device, the edges 26 and 27 fit against the forehead and the frame 23 rests on the bridge of the nose. The pivot members 20 occur substantially opposite the temples. The cheek pieces 21 and frame 23 as a unit may be readily raised or lowered by swinging movement on the pivots 20 and may even occupy a position on top of the head while the harness remains in place on the head and protection for the eyes is unnecessary. The frame or hood 23 may be adjusted to any desired angle by pressing the grips 35' toward each other and thus disengaging the lugs 37 from the openings 38, following which

the frame 23 is arranged in the proper position and the grips released so that the lugs 31 will engage the adjacent openings 38, thus effectively holding the frame or hood in the desired adjusted position. It will be realized that the spring arms 35 and 36 of each spring 34 tend to separate at their free ends so that such ends, when in use as in Figure 4 are under tension.

Various changes may be resorted to provided they fall within the spirit and scope of the invention.

I claim as my invention:—

1. Apparatus of the class described having side members, a protector frame having end portions, U-shaped spring members providing arms between which the end portions are disposed, pivot members passing through the end portions, side members and springs, means of interengagement between the side members and one of the spring arms, and a lens frictionally engaged marginally by the other spring arms to hold the lens in place.

2. Apparatus of the class described having side members, a protector frame having end portions, U-shaped spring members providing arms between which the end portions are disposed, pivot members passing through the end portions, side members and springs, means of interengagement between the side members and one of the spring arms, a lens frictionally engaged marginally by the other spring arms to hold the lens in place, said end portions having notches engaged by the bridges of said springs.

3. Apparatus of the class described having side members, a protector frame having end portions, U-shaped spring members providing arms between which the end portions are disposed, pivot members passing through the end portions, side members and springs, means of interengagement between the side members and one of the spring arms, a lens frictionally engaged marginally by the other spring arms to hold the

lens in place, said means of interengagement comprising a multiplicity of openings in the side members, and lugs on the adjacent spring arms.

4. Apparatus of the class described having side members, a protector frame having end portions, U-shaped spring members providing arms between which the end portions are disposed, pivot members passing through the end portions, side members and springs, means of interengagement between the side members and one of the spring arms, a lens frictionally engaged marginally by the other spring arms to hold the lens in place, said end portions having notches engaged by the bridges of said springs, said means of interengagement comprising lugs 15 on the outer spring arms, and a multiplicity of openings in the side members engageable by the lugs, the side members having enlarged slots through which the pivots pass, and the adjacent arms extending forwardly beyond said protector 20 frame to enable slipping engagement.

5. Apparatus of the class described having mounting means engageable with the head, a protector frame having end portions, U-shaped spring members providing arms between which the end portions are disposed, pivot members passing through the end portions, mounting means and springs, one of the spring arms being tensioned for engagement with said mounting means to retain the latter in different positions. 25

6. Apparatus of the class described having mounting means engageable with the head, a protector frame having end portions, U-shaped spring members providing arms between which the end portions are disposed, pivot members passing through the end portions, mounting means and springs, one of the spring arms being tensioned for engagement with said mounting means to retain the latter in different positions, and a lens held in place by one of the 40 spring arms. 35

HONEL A. JACKSON.
